UNITED STATES PATENT OFFICE.

THOMAS H. RHOADS, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Original application filed December 23, 1924, Serial No. 757,688. Divided and this application filed June 19, 1926. Serial No. 117,147.

My invention relates to certain improvements in driers, particularly driers for drying ceramic ware and other articles.

This application is a division of an application for patent filed by me on December 23, 1924, under Serial No. 757,688.

The object of the present invention is to so construct a drier that the air will be circulated first through one compartment and then through another compartment, and recirculated in said compartments. The articles being dried are subjected to a controlled circulation of air to prevent a too rapid drying and cracking.

In the accompanying drawings:

Fig. 1 is a transverse sectional view of a double drier, in which the air is circulated, on the line 1—1, Fig. 3;

Fig. 2 is a sectional view on the line 2—2, Fig. 1;

Fig. 3 is a sectional plan view on the line 3—3, Fig. 1; and

Fig. 4 is an enlarged detail showing the hinged door.

The drier shown in the drawings is what is known as a truck drier, in which articles are mounted on trucks that are traversed through the drier.

The drier casing 1 is divided by a central, vertical portion 2 into two drying chambers *a* and *b*, the drying chambers being similar in construction.

The trucks 3 are of the ordinary type, each truck having wheels 4 and trays 5, on which the ceramic ware or other articles are mounted.

Tunnels *c*—*c*, through which the trucks are moved, are each formed by a casing having side members 6—6^a and tops 7. The side members are open opposite the carrying portion of each truck. In order to close these openings, pivoted doors 8 are provided. These doors are pivoted at 9. The doors 8 can be moved to any position desired to allow more or less air to circulate across the trucks and in contact with the articles being dried.

The side members 6 of the tunnels are extended to the top of the drier and separate the chambers *a* and *b* from their heating chambers *e*. In the extensions of the

side members 6 are fan openings, in which are located the circulating fans 14 and 14^a mounted on shafts 15.

In the heating chambers are steam pipes 55 17, which heat the air in circulation.

In the present instance each drying chamber *a* and *b* is made in two sections by a vertical partition 19. At the bottom of said partition are passages 20 and 21, formed by 60 a series of spaced slats. The air intakes are shown at 22 and the exhaust flues are shown at 23.

The fans are rotated rapidly. Consequently, there is a rapid circulation of air 65 through the heating chambers and the drying chambers. This rapid circulation of air is desirable in order to heat the casing of each tunnel and to change the air in circulation. The circulation of the air, however, 70 is too rapid to allow the currents of air to come in direct contact with the articles on the trucks.

By regulating the position of the doors 8, a portion of the air is allowed to travel 75 across the tunnel from one side to the other and in contact with the articles being dried.

The air in circulation in the drier passes around the tunnel in the section *a'* of the drying chamber *a*, then through the passage 80 20 in the partition 19 into the adjoining section *a'*, and up through this section, and through the suction fan 14^a. The air then passes down through the heating chamber of the section *a'*, though the openings 21 in 85 the partition 19, up through the heating chamber of the section *a'*, and through the fan 14 into the section *a'*.

In practice, it has been found that this method of drying articles prevents cracking or warping of the articles. By adjusting the doors 8, the amount of heated air passing in contact with the articles can be regulated to a nicety.

It will be understood that the drier can 95 be of any length desired and that the air in circulation in the different compartments may be regulated to dry the articles properly as they pass through the drier.

I claim:

1. The combination in a drier, of two drying sections placed side by side; a circulat-

ing fan for each section; a tunnel extending through both sections; trucks in the tunnel for the articles to be dried; a vertical partition having two openings therein, the air circulating first through one section and then through the other section, the air returning to the first section; and means for allowing a certain proportion of the air to pass through the tunnel in direct contact with the articles being dried.

2. The combination in a drier, of two vertical partitions, one partition extending the full height of the drier and dividing the drier into a drying chamber and a heating chamber; a horizontal partition connecting the two vertical partitions and forming with said partitions a longitudinal tunnel, the

vertical partitions having openings to allow air in circulation to pass into the tunnel; doors at the openings to regulate the passage of air; circulating fans in the first mentioned vertical partition, above the tunnel; a transverse partition dividing the drier into two sections; and two openings in the lower end of said transverse partition, one forming a communication between the two drying sections and the other forming a communication between the two heating sections of the drier, the air in circulation passing first through one section and then through the other section and returning to the first section.

THOMAS H. RHOADS.
